UNITED STATES PATENT OFFICE.

CHARLES B. GARRETT, OF MINNEAPOLIS, MINNESOTA, ASSIGNOR OF ONE-HALF TO MARTIN DYKE, OF SAME PLACE.

ELECTRIC DETECTOR FOR VALVES.

SPECIFICATION forming part of Letters Patent No. 681,211, dated August 27, 1901.

Application filed March 20, 1900. Serial No. 9,369. (No model.)

To all whom it may concern:

Be it known that I, CHARLES B. GARRETT, a citizen of the United States, residing at Minneapolis, in the county of Hennepin and State 5 of Minnesota, have invented certain new and useful Improvements in Electric Detectors for Valves; and I do hereby declare the following to be a full, clear, and exact description of the invention, such as will enable others skilled in 10 the art to which it appertains to make and use the same.

My present invention has for its object to provide a detecting device for indicating when a valve has been moved from a set position; 15 and to this end it consists of the novel devices and combinations of devices hereinafter described, and defined in the claims.

This detecting device is especially designed for use in connection with fire-protecting systems. In such systems certain of the water-distribution pipes are provided with valves, which in the most instances should be normally left in open positions, but in some cases should be left set in closed positions. 25 In all such cases it is of the greatest importance that the proper persons should receive notice whenever one of these valves is moved from its set or normal position. By my invention the movement of a valve from its set 30 position is automatically indicated, and hence tampering with the said valves is prevented or at least prevented from having serious consequences.

The invention in its preferred form is illustrated in the accompanying drawings, wherein like characters indicate like parts throughout the several views.

Figure 1 is a view, partly in elevation and partly in vertical section, showing a portion 40 of a water-distribution pipe, a valve controlling the same, and my improved lock and alarm device or enunciator applied in working position for coöperation with the said lock. Fig. 2 is a transverse section on the line $\alpha^2 \alpha^2$ of Fig. 1; and Fig. 3 is a view, partly in side elevation, partly in vertical section, and partly in diagram, showing a modified construction.

The numeral 1 indicates what may be assumed to be a vertically-disposed stand-pipe

or water-distribution pipe of an automatic fire-protective system, although it may of course be any sort of a water-distribution pipe and may extend in any direction.

The numeral 2 indicates a valve in the pipe 55 1, which may be of any suitable or ordinary construction adapted to be opened and closed by the simple rotary movement of the hand-wheel or valve-mover 3. We may assume that the valve 2 is normally set in an open 60 position and that it is desirable to sound an alarm or actuate an enunciator whenever the said valve is closed or rather whenever the valve-mover or hand-wheel 3 is turned from its normal position. 65

For coöperation with the hand-wheel 3 a supporting-head 4, which is provided at its segmental upper surface with a segmental channel-piece 5, is supported, as shown, from the floor 6 by means of a tubular standard 7. 70 The standard 7 has right-hand threads at one end and left-hand threads at the other, and at its upper end it has screw-threaded engagement into a seat 8 in the lower portion of the head 4, while at its lower end it has 75 screw-threaded engagement with the seat 9, formed in a base plate or casting 10, which is secured to the floor 6. Preferably jam-nuts 11 and 12 work, respectively, on the upper and lower ends of the standard 7 to lock the 80 said standard where set within its screw-threaded seats.

The peripheral portion of the hand-wheel 3 is preferably formed approximately square or rectangular in cross-section, and it works 85 closely between the flanges of the segmental channel-piece 5, as best shown in Fig. 2. At one point the flange of the wheel 3 is formed with a radial seat 13, and in this seat a lock plunger or head 14 is mounted to work, with 90 its stem 15 projecting inward through the wheel-rim and provided with a finger-piece, as shown, in the form of a ring 16. A spring 17, compressed within the seat 13 between the lock head or plunger 14 and the bottom 95 of the said seat, tends to normally hold said lock-head outward to its limit. At its central portion the segmental channel-piece 5 has a depression 18, which is adapted to receive the outer end of the lock head or plun- 100

ger 14 to lock the wheel 3 against rotation. As shown, a felt or pliable packing 19 is placed in the bottom of the depression 18.

The head 4 is recessed at 20, just below the 5 depressed portion 18 of the segmental channel 5. In the bottom of the recess 20 is a block 21 of rubber or insulating material, through which, in the construction illustrated, metallic plugs 22 are passed. To one plug 22 10 an electrode or contact-piece 23 is secured and to the other plug 22 an electrode or contact in the form of a leaf-spring 24 is secured. The free end of the spring-contact 24 normally stands out of engagement with 15 the free end of the contact 23, being held in such position by the lock head or plunger 14, which engages an insulating-finger or projection 25, which, as shown, is carried by the said spring-contact 24. The spring 17 is of 20 course strong enough to overcome the tension of the spring-contact 24. Hence the circuit is normally broken between the contacts 23 and 24. However, when the lock head or plunger 14 is drawn inward, as is 25 necessary in order to turn the wheel 3, the contact 24 will spring into engagement with the contact 23 and close the circuit between them. Circuit-wires 26 connect to the metallic plugs 22, and in this circuit 26 is a battery 27 and an electrically-operated alarm-bell or gong 28. The gong 28 may of course 30 be located at any suitable adjacent point—such as the office of the building, the home of the owner or watchman or other person, 35 or at the police or fire station.

With the above-described construction it is impossible to unlock the wheel or valve-mover 3 without closing the circuit 26 and sounding the gong. Of course an enunciator 40 of some other form—such, for instance, as a pointer and dial or other visual side indicator—might be employed, and, if desired, enunciators may be used in connection with the alarm device to indicate just which valve 45 has been tampered with or moved.

The modification shown in Fig. 3 is nearly the same as in Fig. 1, with few exceptions. This construction comprises a normally-closed circuit 29 and a normally open circuit 30. The circuit 29 involves a battery 31, a magnet 32; together with the plugs 22 and the spring-contact 24, secured to one of the plugs 22, which is held in engagement with a contact-piece 33, secured to one of the 55 plugs 22 by the lock head or plunger 14, which engages the insulating finger or projection 25, carried by the spring-contact 24, which in this construction has been made long enough to just reach between said plunger 60 14 and the spring-contact 24 when said spring 24 is in engagement with said contact

33. The circuit 30 involves the battery 34, the electrically-operated alarm-bell or gong 28, the circuit-closing lever 35, and the contact-pieces 36. The contact-lever 35 is normally held against the tension of a light spring 37 out of contact with the contact-pieces 36 by the normally-energized magnet 32.

With the above-described construction it is impossible to unlock the wheel or valve-mover 3 without breaking the circuit 29, and the magnet 32 being deenergized will release the lever 35, which under the action of the spring 37 will be thrown into engagement with the contact-pieces 36, thereby closing 75 the circuit 30 and sounding the alarm 28.

Other changes may also be made within the scope of my invention.

To apply the head 4 and segmental flange 5 to working position with the flanges of the 80 channel 5 embracing the periphery of the hand-wheel, the standard 7 may be screwed into its seats 8 and 9 farther than shown in Fig. 1, and then after the parts are properly located the said standard may be adjusted 85 as shown in the drawings. It will be further understood that the lock device may take various forms and may be applied to valve-movers of various forms.

What I claim, and desire to secure by Letters Patent of the United States, is as follows:

1. The combination with a hand-wheel for moving a valve, and an adjacent relatively-fixed support, of a spring-pressed and finger-released lock for locking said hand-wheel to 95 said support, an electric alarm or enunciator having circuit connections to a pair of electrodes or contacts adapted to make and break the circuit, one of which electrodes is normally held in one of its extreme positions 100 and is released by the releasing movement of said lock to actuate said alarm, substantially as described.

2. The combination with the hand-wheel 3 actuating a valve and provided with the recess 13, of the spring-pressed lock-plunger working in said recess 13 and provided with a projecting finger-piece, the head or support 4 having the recess 20 and flanged segmental upper surface 5, a recess in said section 5 normally receiving said lock-plunger 14, and the electrical alarm or enunciator comprising the electrodes 23 and 24, the latter having or being subject to a projection 25 which is pressed by the said lock 14, said 115 parts operating substantially as described.

In testimony whereof I affix my signature in presence of two witnesses.

CHARLES B. GARRETT.
